UNITED STATES PATENT OFFICE.

LOUIS W. KARLEN, OF DES MOINES, IOWA.

FOLDER AND FASTENER THEREFOR.

Application filed March 21, 1922. Serial No. 545,603.

To all whom it may concern:

Be it known that I, LOUIS W. KARLEN, a citizen of the United States, and a resident of Des Moines, in the county of Polk and 5 State of Iowa, have invented a certain new and useful Folder and Fastener Therefor, of which the following is a specification.

The object of my invention is to provide a folder and fastener device therefor of simple, durable and comparatively inexpensive 10 construction.

More particularly, my invention relates to a type of folder especially adapted for containing a number of loose sheets or letters 15 all relating to a certain transaction. For example, in connection with the insurance business, the references to the policy, letters to the agents and everything concerning the policy are all filed in a single file.

20 It is my intention to provide such a file, which is arranged with a sheet of comparatively tough material folded intermediate of its ends, so as to form a front and back, the tough sheet of paper being provided with a 25 fastener, which is very simple, so that the letters and other sheets of paper containing data thereon may be secured thereto and properly held in the file.

Still a further object is to provide a fastener device for a file arranged to have its 30 main body portion secured to the paper on the outside thereof, and having tongues extended through the paper and bent upon themselves for securely holding the fastener in proper position, the fastener being further provided with a pair of tongues extended through the paper and so arranged that it is formed integral with the main body 35 portion of the fastener and is simple in construction and can be made by stamping.

Still a further object is to provide a fastener for a folder including a pair of strap members arranged to be spaced from each other and arranged to have their ends extended through the paper and clinched for holding the straps to the paper, whereby a 45 pair of tongues may be located therebetween and secured thereto and arranged to extend through the paper, whereby they may be 50 manipulated for securely fastening loose sheets of paper within the file.

With these and other objects in view, my invention consists in the construction, arrangement and combination of the various 55 parts of my device, whereby the objects con-

templated are attained, as hereinafter more fully set forth, pointed out in my claim, and illustrated in the accompanying drawings, in which:

Figure 1 is a perspective view of my improved folder and fastener device therefor, parts being shown in section to better illustrate the construction.

Figure 2 is a perspective view of a portion of the front and back of the folder, showing the inner end of one of the papers filed in 65 the folder.

Figure 3 is a perspective view of the fastener device; and

Figure 4 is a plan view showing the fastener device secured to the back side of the 70 folder.

In the accompanying drawings, I have used the reference character A to indicate generally a sheet of paper of greater length 75 than width, which is folded intermediate of its ends, as at 10, so as to provide a front sheet 11 and a back sheet 12.

In this connection, it may be mentioned that especially in insurance work, all of the 80 papers and records relating to a certain policy are all filed in a single file. I have employed my folder and fastener device for insurance work, and find that it is very efficient and is far more advantageous than some of the 85 present filing devices.

My improved fastener for the folder is preferably made by dies and is formed of very thin sheet metal. The fastener includes a pair of strap portions 13 and 14 spaced from 90 each other. Each of the ends of the strap portions 13 and 14 are bent at right angles to themselves, so as to form the tongues 15, which are bevelled or inclined as at 16.

Received between the strap portions 13 95 and 14 and formed integral therewith are the tongues or straps 17 and 18. The tongues 17 and 18 are connected together at their portion which is secured to the straps 13 and 14, so as to make a substantially U-shaped member, when the parts are in the position shown in Figure 3 of the drawings.

In the front 12 of the folder, I provide a central opening 19 through which is extended the tongues 17 and 18. The tongues 15 are extended through slits formed in the front sheet 11 and are then clinched or bent upon themselves for securely holding the fastener devices to the folder. The 110

sharpened edges 16 of the tongues 15 cause the paper to be slit, so as to permit the tongues 15 to be extended therethrough.

In Figure 1 of the drawings, the tongues 5 15 are shown bent over in dotted lines. The two strap members 13 and 14 are on the outside of the folder. By making the entire fastener device of a single piece of metal, I am able to use a much thinner metal and 10 yet have the parts of sufficient strength, so that the tongues 17 and 18 may be folded over a great many times without breaking. The arranging of the tongues 17 and 18 between the straps 13 and 14 permit me to 15 make the entire fastener of a single piece of metal by stamping the same from sheet metal.

In Figure 2 of the drawings, I have shown the end of a letter or sheet of paper 20, which is provided with a central opening 21, so that the tongues 17 and 18 may be extended therethrough and bent over for 25 securely holding the letters or sheets 20 in position.

It will be seen that when the front 11 and 25 the letters secured thereon are bent over, so that the folder is folded and the front sheet 11 rests upon the back sheet 12, all of the letters or sheets received between the front 30 and back of the folder and secured to my fastening device will lie flat and be held in proper position.

The securing of the fastening device to the front sheet 11 requires the letters to be 35 filed with the written matter face downward or against the inner side of the front sheet 11. The additional letters from time to time are filed upon the previous letters, so that the first letter placed in the file or 40 record is near the front side of the folder, and it is not necessary to remove any of the previous letters in order to file any additional letters.

In Figure 4 of the drawings, I have 45 shown the fastener device as secured to the back 12 of the folder. In that case, the letter is filed with the back thereof against the inner side of the back 12 and face upward. Each additional letter is placed 50 directly on top of the previous letter filed, so that the last letter is always on top face upwards, while in Figure 2, the last letter, when the file is opened, would always be on top face downward.

It will be seen that I have provided a 55 folder and fastener device therefor of very simple construction and so arranged that the

60 filing may be easily done without the inconvenience of removing any of the previous letters or separating them, as is sometimes required in the present filing systems.

The arranging of the straps 13 and 14 on the outer side of the folder with all the 65 tongues and fastening devices on the interior of the folder, permits me to file a great number of folders close together, without any possible chance of any of the fastening devices becoming hooked or engaging the other or adjacent folders.

It will be seen that there are no sharp 70 edges or ends left on the exterior of the folder, which might scratch or engage the next adjacent folder.

Some changes may be made in the construction and arrangement of the various 75 parts of my device without departing from the essential features and purposes of my invention, and it is my intention to cover by my claim, any modified forms of structure or use of mechanical equivalents, 80 which may be reasonably included within its scope.

I claim as my invention:

A folder and fastener therefor including 85 a sheet of paper of greater length than width folded midway between its ends for forming a front and back member, a fastener device of a single piece of material, said fastener device including a pair of spaced strap portions having their ends 90 bent at right angles, said ends being tapered and extended through the paper near the fold therein and bent upon said strap members for engaging the paper therebetween, said ends being received on the inner side 95 of the folder, whereby no ends or edges will be left on the exterior of the folder, a pair of tongues formed from the single piece of material and arranged to be received between said strap portions midway between 100 their ends, and a connecting web formed from the piece of material for connecting the strap portions in spaced relation and for holding the tongues in position, said pair of tongues having their ends tapered 105 and being extended through the paper in the same direction as the ends of the said strap members, so that flat sheets may be secured thereon and by folding the tongues in opposite directions the sheets will be 110 permanently held in position between the front and back members of the folder.

LOUIS W. KARLEN.
